(57) **CLAIM**

The ornamental design for a finial, as shown and described.

DESCRIPTION

FIG. 1 is a side view of the finial with all sides being the same, the stippling representing a contrasting color.

FIG. 2 is a top view thereof; and,

FIG. 3 is a bottom view thereof.

The broken lines represent environment of use and form no part of the claim.

1 Claim, 2 Drawing Sheets Fig. 1

Fig. 2
